UNITED STATES PATENT OFFICE

LOUIS BENINTENDE, OF WOODBRIDGE, NEW JERSEY

STEPLADDER

Application filed November 16, 1928. Serial No. 319,966.

The present invention relates to step ladders and has for an object to provide a device of this character of simple construction, consisting of two parts that can be manufactured and readily assembled to contemplate the use of a suitable platform or ledge together with means for supporting the same in a horizontal position thus providing a structure particularly adapted for the use of painters, paperhangers and the like.

Among other features the invention comprehends a step ladder which when folded will be in a compact form so that it can be easily carried from one place to another and which can be readily set up in position for use, the platform employed in connection with the step ladder being also of a foldable nature and when open for use supplying an efficient support for the material to be used by the workman.

The invention has for a still further object to provide an article of this character which will insure safety for the person engaged in that work and generally to provide a simple and durable ladder that will meet all the requirements as furnished by a strong and steady scaffolding upon which the workman may stand while at work.

Other objects and advantages reside in the special construction, combination and arrangement of the various elements forming the invention as more fully hereinafter described and claimed, reference being had to the accompanying drawings forming part hereof wherein like numerals refer to like parts throughout, and in which:

Figure 1 is a front elevational view,

Figure 2 is a vertical sectional view toward one side of the ladder, taken substantially along a line 2—2 of Figure 1,

Figure 3 is a similar view showing the ladder in folded position,

Figure 4 is a horizontal sectional view taken substantially along a line 4—4 of Figure 3,

Figure 5 is a fragmentary detail in perspective of the pivotal support for one side of the platform,

Figure 6 is a perspective view of the combined shelf and rear support for the platform,

Figure 7 is a perspective view of the slotted bracket providing a pivotal support for the ends of the platform, and

Figure 8 is a perspective view of the platform.

Referring now to the drawings in detail, wherein for the purpose of illustration I have disclosed a preferred embodiment of the invention, the numerals 5 and 6 designate respectively the front and rear legs of a folding step ladder hingedly connected at their upper ends as indicated at 7 whereby to permit the lower ends thereof to swing outwardly away from each other.

The front legs 5 are provided with the usual steps 8 and the rear legs 6 are secured in spaced parallel relation by means of horizontal brace members 9. A bracket 10 is secured to the forward edge of each of the rear legs 6, said brackets being substantially of a U-shaped formation in cross section, as clearly illustrated in Figure 7 of the drawings, and is secured to the legs by nails or screws inserted through openings 11 formed in the base portion of said brackets.

Each of the parallel side portions 12 of the bracket are provided with vertically extending slotted openings 13 and a similar opening is formed in the legs registering with said slotted opening. The openings in the bracket at each side of the ladder are adapted to receive the opposite ends of a rod 14 extending outwardly from the opposite sides of a tilting platform 15.

The platform 15 is constructed of a pair of longitudinally extending spaced parallel frame members 16 upon the upper edge of which planks 17 are secured. A horizontal rod 18 extends between the pair of front legs 5.

5 and is adapted for receiving a forwardly disposed notch 19 formed in the lower edge of the frame members 16 of the platform and when secured in the manner as illustrated in 5 Figure 2 of the drawings, it will be apparent that the platform will serve to retain the front and rear legs of the ladder in spaced relation. To the lower end of each of the rear legs 6 is pivotally attached the lower ends of 10 the legs 20 of a supporting member, the legs of the support being of sufficient length to extend slightly above the rear legs 6, said legs 20 being connected at their upper ends to a shelf 21 having its forward edge extending 15 forwardly of the legs and supported by a brace or bracket 22.

A horizontally disposed U-shaped rod 23 is carried by the legs 20 of the support with the ends of said rods bent outwardly and inserted through openings formed in the respective legs, the outer end of said rod being threaded for receiving nuts 24 whereby to secure offset portion of the rod 23 at a horizontal plane with the ends thereof.

25 The rod 23 is disposed at a proper position upon the legs 20 for receiving notches 25 formed rearwardly in the lower edge of the frame members 16 of the platform whereby to support the rear end of the platform in a 30 horizontal position.

It will be observed from an inspection of 35 Figure 6 of the drawing, that the offset portion of the U-shaped rod 23 is disposed forwardly of the legs 20 in order that the platform may be swung into a substantially vertical position, as illustrated in Figure 3 of the drawings, when the legs 5 and 6 of the ladder and the legs 20 of the support are folded fully inwardly against each other.

40 When the ladder is in open position the ends of the rod 14 will be seated within the lower portion of the slotted opening 13 and in order to fold the ladder, the rear end of the platform is raised upwardly releasing the 45 notches 25 from the rod 23 whereby the legs 20 will be permitted to swing inwardly toward the rear legs 6.

Upon the completion of this movement the rear end of the platform may then be tilted 50 downwardly thus reaching the forward legs 5 and permitting the same to be folded together with the legs 6.

It will also be observed that from an inspection of Figure 4 of the drawings that the 55 legs 20 of the supporting member are disposed inwardly of the rear leg 6 and the platform is of a width less than the space between the legs 20 so that the platform, when folded, may be disposed between said legs.

60 By reason of this construction, the ladder may be folded in a substantially compact manner.

It is obvious that my invention is susceptible to various changes and modifications in 65 construction without departing from the

spirit of the invention or the scope of the appended claims, and I accordingly claim all such forms of the device to which I am entitled.

Having thus described my invention, what 70 I claim as new is:

1. A folding ladder of the class described comprising front and rear leg members hingedly connected at their upper ends, a tilting platform pivotally mounted for vertical swinging movement to said rear leg members, said platform having notches formed along its lower edge, a supporting member comprising a pair of legs pivotally connected at the lower ends of said rear leg members, and means carried by the legs of said supporting member and said front leg for receiving the notches of the platform whereby to support the same in a horizontal position. 75

2. A folding ladder of the class described comprising front and rear leg members hingedly connected at their upper ends, a tilting platform pivotally mounted for vertical swinging movement to said rear leg members, said platform having notches formed along its lower edge, a supporting member comprising a pair of legs pivotally connected at the lower ends of said rear leg members, and means carried by the legs of said supporting member and said front leg for receiving 80 the notches of the platform whereby to support the same in a horizontal position, said means comprising horizontal rods extending transversely between the respective leg members, the rod carried by said supporting members being of a U-shaped formation and arranged with its intermediate portion disposed forwardly of the pivotal mounting of the platform whereby to prevent interference by the rod for positioning the platform vertically when the latter is arranged in folded 85 position. 90

100

105

3. A folding ladder comprising front and rear leg members hingedly connected at their upper ends, brackets attached to each of the rear leg members, said legs and the brackets having alined vertically extending slotted openings formed therein, a tilting platform having a horizontal rod extended transversely thereof intermediate its ends with its opposite ends disposed in the openings of said bracket, means for pivotally supporting said legs, said platform having notches formed along its lower edge, a rod disposed transversely between the forward leg members and adapted for insertion in one of said notches, and a supporting member comprising a pair of legs pivotally connected at their lower ends to the lower portion of said rear leg members and having a shelf disposed at the upper end of said legs, said supporting member extending slightly above said front and rear leg members whereby to permit the shelf to be moved into position above the upper end thereof, and a U-shaped rod disposed hori- 115

115

130

zontally between the legs of said supporting member with its offset portion disposed forwardly of the legs and adapted for insertion in one of the notches of said platform whereby to support the rear end thereof in a horizontal position, the legs of said supporting member being adapted for movement into a position between the rear leg members with the offset portion of said U-shaped rod disposed forwardly of the pivoted rod of the platform when each of the legs are disposed in folded position.

In testimony whereof I affix my signature.
LOUIS BENINTENDE.
